THREAD CONTROLLER FOR WEFT REPLENISHING LOOMS

Filed March 25, 1940

UNITED STATES PATENT OFFICE

2,224,594

THREAD CONTROLLER FOR WEFT
REPLENISHING LOOMS

Albert Cederlund, Worcester, Mass., assignor to
Crompton & Knowles Loom Works, Worcester,
Mass., a corporation of Massachusetts

Application March 25, 1940, Serial No. 325,795

11 Claims. (Cl. 139—256)

This invention relates to thread controllers for weft replenishing looms, more particularly the thread of the outgoing bobbin, and it is the general object of the invention to provide means for positively moving the thread into the zone of action of a pneumatic thread remover.

In weft replenishing looms a thread extends from the selvage to the shuttle eye of the depleted bobbin at the time of transfer and it is necessary to remove this thread to prevent the same from being drawn into the shed. It has been proposed heretofore to employ pneumatic means for drawing the thread away from the lay and out of the path of the shuttle. It is an important object of my present invention to provide a thread placer operative on transferring beats of the loom to move the thread into a pneumatic tube located preferably on the lay and under the shuttle path.

It is a further object of my present invention to provide a pneumatic tube and elongated slot in the upper side thereof to receive a thread placer which moves down through the slot to a position near the bottom of the tube, thereby drawing part of the thread into the tube and taking up sufficient slack to tighten the thread so that it will be properly located for the thread cutter.

Weft replenishing mechanisms usually include in their construction the so-called shuttle feeler which acts to prevent transfer if the shuttle is improperly placed to receive the incoming bobbin. The shuttle feeler usually includes a part movable across the path of the shuttle preparatory to transfer. If the shuttle is properly placed the shuttle feeler has a completed motion and transfer ensues, but if the shuttle is misplaced it interrupts motion of the shuttle feeler and associated mechanism prevents transfer. It is a further object of my present invention to control the aforesaid thread placer by the shuttle feeler in such a way as to effect movement of the thread placer into a pneumatic tube when the shuttle is correctly placed for transfer, but prevent such movement if the shuttle is improperly located. This control is also instrumental in preventing the thread placer from moving into the path of the shuttle if the latter is misplaced. This last feature of my invention depends upon the fact that it is the latter part of a complete motion of the shuttle feeler which gives the thread placer its operating movement.

In a type of automatic loom which has gone into extensive use a lever normally at rest has an operating movement preparatory to transfer for the purpose of setting certain parts of the

replenishing mechanism. This lever is normally at rest and is lifted during the first part of a pick in which a transfer is to occur. It is a further object of my present invention to provide positioning devices for the thread placer connected to the lever and operated by it to set the thread placer for operation by the shuttle feeler.

It is a further object of my present invention to provide a pneumatic thread receiver with an inlet which serves the dual purpose of affording entry of the thread placer into the receiver and at the same time permit an inrush of air to act on the thread.

With these and other objects in view which will appear as the description proceeds, my invention resides in the combination and arrangement of parts hereinafter described and set forth.

In the accompanying drawing, wherein a convenient embodiment of my invention is set forth;

Fig. 1 is a side elevation of a weft replenishing mechanism having my invention applied thereto as viewed from the center of the loom, certain parts being in section,

Fig. 2 is a detailed front elevation in the direction of arrow 2, Fig. 1,

Fig. 3 is a plan view in the direction of arrow 3, Fig. 1,

Fig. 4 is a detail horizontal section on an enlarged scale on line 4—4 of Fig. 2,

Fig. 5 is an enlarged vertical section through the pneumatic tube showing the thread placer and thread in the tube and taken on line 5—5 of Fig. 3,

Fig. 6 is a detail view of a part of the setting mechanism for the thread placer,

Fig. 7 is a diagrammatic view showing the relation of the shuttle and thread controller to the cloth being woven and other parts of the loom, and

Fig. 8 is a detail view partly in section showing the relation of the thread, its placer and the pneumatic tube as they appear in a transferring operation of the loom.

In carrying my invention into effect, I provide a loom frame 10 which supports foot 11 of a magazine designated generally at M. This magazine may be of the type shown in my prior Patent No. 2,128,915 and in the present instance provides two distinctive types of reserve bobbins only one of which is indicated at B in Fig. 1. The magazine includes in its construction a transfer arm 12 pivoted as at 13 and having attached thereto a latch holder 14 provided with a latch 15. The lay L swings about an axis low in the loom frame and reciprocates horizontally toward

and from forward or beat-up position. The transfer is operated by a dagger 16 on the lay as the latter approaches front center or beat-up position on the transferring pick of the loom. A 5 shuttle S provided with a bobbin W of the usual construction is picked back and forth across the lay and travels along a shuttle race 17.

The mechanism for setting the latch and determining the position of the shuttle along the 10 length of the lay includes a lever 20 normally at rest in low position to be lifted by a dog 21 on a regularly rocking lever 22 which has a rising motion every second beat of the loom starting when the shuttle to be replenished is on that side 15 of the loom opposite the magazine, or when the depleted shuttle is traveling toward the magazine. Lever 20 has a stud 23 received by a yielding rod head 18 having two parts 24 and 25 ordinarily held together by a spring 26 so that up 20 motion of the lever will raise a rod 27 connected to the head 18. When relative motion between the rod and lever is necessitated by a misplaced shuttle the parts 24 and 25 separate as indicated in dotted lines in the lower part of Fig. 1 so that 25 the stud can move upwardly between said parts.

The shuttle feeler and latch placer are mounted 30 on a setting lever 30 rockable about a fixed pivot 31 and pivoted as at 32 to a rod head 33 on the upper end of rod 27. Moving with the lever 30 is a latch lifter 34 for engagement with the latch 15, and a shuttle feeler 35. The setting lever is normally in the down full line position shown in Fig. 1, but when a transfer is initiated lever 30 moves to the dotted line position of that 35 figure to lift the latch and also place the shuttle feeler in a position for detecting whether the shuttle is properly boxed. That part of the mechanism which is operated by rod 27 may be the same as shown in prior Patent 2,162,290 and 40 of itself forms no part of my present invention except as it cooperates in a manner set forth hereinafter with the thread placer.

The loom is also provided with a thread accumulator 40 which may be formed as a hollow 45 cylinder from which extends a tube 41 provided for the purpose of directing threads into the accumulator. The latter is connected to mechanism not shown herein for creating a partial vacuum therein as shown in co-pending application Serial No. 199,169. It is thought sufficient 50 for present purposes to state that subatmospheric pressures will be created in the accumulator and therefore tube 41 at the proper time to remove a thread from the lay, preferably during the picking which immediately follows a transferring operation. I do not wish however to be limited to any particular means or time of operation for the creation of reduced pressures in the accumulator, since it is sufficient if these pressures exist 55 at those times in the operation of the loom when the thread of the outgoing bobbin is capable of removal from the lay.

In Fig. 7 the shuttle S is shown as having a 60 weft thread T extending therefrom toward the adjacent selvage C, and the shuttle has a cutting plate 45 across which the thread extends. A cutter blade 46 is moved toward the plate at the time of transfer to sever the thread and permit the outgoing bobbin to unthread the shuttle eye 70 47. The remainder of the thread extending toward the selvage lies along the shuttle race 17 and over the thread remover forming an important part of my present invention and to be described hereinafter.

75 The matter thus far described, except as in-

dicated hereinafter, is of usual construction and of itself forms no part of my present invention and reference may be had to the aforesaid patent and co-pending application for a further understanding and structure of the operation of the 5 setting lever 30 and the thread accumulator 40.

In carrying my present invention into effect I provide a U-shaped tube 50 the upper part of which is located in a slot 51 extending transversely across the lay under the path of the shuttle. The lower part of tube 50 fits into a rubber tube 41 while the upper part if provided with a longitudinal slot 52 and closed at its rear end as at 53. It is therefore apparent that whenever subatmospheric pressures are created in the 15 accumulator 40 there will be an inrush of air into the slot 52. This slot as shown in Fig. 1 extends across the greater part of the shuttle race and as shown more particularly in Fig. 7, it will lie under that part of the weft thread which extends from the selvage to the shuttle eye.

The placer mechanism for the thread is mounted on the lay and comprises a stand 55 bolted or otherwise secured to the front of the lay as at 56 and affording support for the tube 25 50 which is welded or otherwise secured to the stand. The latter has pivoted thereto as at 57 an upright lever 58 the upper arm 59 of which has secured thereto a thread placer wire 60. This wire is formed as shown more particularly in Fig. 30 8 and has a relatively high straight horizontal section 61 which ends in a downwardly inclined part 62 from which extends rearwardly a substantially straight and normally horizontal section 63. In order to prevent this latter section 35 from lying too closely along the bottom of tube 50 a slight downward bend 64 may be formed in the wire. As shown in Fig. 8 the downward bent part 62 of the wire normally lies near the forward end of the slot 52.

The lower arm 10 of lever 58 is pivoted as at 11 to a rearwardly extending hook 72 passing through a slot 73 in the under side of the lay in which is located the lower part of tube 50. This hook projects beyond the rear part of the 45 lay and is positioned for engagement by a placing lever 75 secured to a small shaft 76 journaled in a bearing bracket 77. Shaft 76 extends substantially parallel to the lay and the outer end thereof carries an arm 78 pivoted to the upper 50 end of a rod 79 the lower end of which is pivoted at 80 to the lever 20. The placing lever 75 may be formed with a pair of spaced plates 81 between which lies a hook engaging plate 82 having two oblique surfaces 83 and 84 which define a lifting 55 shoulder 85, see Fig. 6. The rear end of the hook normally rests on the plate 82 between the side plates 81.

In order to hold lever 58 frictionally to any 60 position to which it may be moved I provide the structure shown in Fig. 4. The stand or bracket 55 has a forwardly projecting arm 88 in which is located the pin defining the previously described pivot 57. This pin extends through a hub 89 on the lever 58 provided with a series of holes 65 90 for the reception of compression springs 91. A cotter pin or the like 92 holds the hub close to the arm 88, while the springs press against this arm 88 and thereby establish frictional contact between lever 58 and its supporting arm 88 sufficient to hold the lever in any position to which 70 it may be moved.

In operation, lever 20 is normally down so that rod 79 is in low position and holds the placing lever 75 to the right as shown in Fig. 1 75

away from the hook 72. The rod 19 is relatively long and extends downwardly to a position not far removed from the axis about which the lay swings. When the exhausted shuttle is on the 5 side of the loom opposite the magazine and the lay is moving from front center rearwardly toward picking position, rod 20 will start upwardly if the loom has been set for a transferring operation. This upward motion of lever 20 raises the 10 rod 19 and causes a left hand rocking of shaft 76 as viewed in Fig. 1, thereby rocking lever 75 to the left so that the plate 82 will move the hook 72 rearwardly to the position shown in dotted lines in Fig. 1. This causes a right hand rocking of 15 lever 58 which raises the thread placer 60 from the normally down position in tube 50 shown in full lines in Fig. 1 to the elevated position shown in dotted lines. It is to be understood that this lifting of the wire or placer 60 occurs while the 20 lay is in the rearward part of its range of motion and before the shuttle reaches the placer.

Assuming that the shuttle will reach proper 25 position for transfer in the shuttle box X, the shuttle feeler 35 will move rearwardly toward the dotted position of Fig. 1 during the latter part of the upward motion of lever 20 through the connections already described and including rod 27 and lever 30. During this rearward motion the shuttle feeler will be free to have a complete 30 motion due to the assumption that the shuttle is properly placed for transfer and a portion of the shuttle feeler designated at 95 in Fig. 3 will engage a part 96 of the placer 60 above the pivot 51 and will therefore rock lever 58 in a left hand 35 direction, referring to Fig. 1, to lower the placer 60.

As the placer descends and enters the slot 52 it will carry a portion of the thread into the tube 50 as suggested in Figs. 5 and 8. These operations occur after the shuttle has been boxed and 40 while the lay is near or in its front center position. Movement of the thread into the tube 50 tightens those parts of the thread extending from the slot 52 to the selvage and to the shuttle eye, 45 thereby insuring location of the thread across the plate 45 when the cutter 46 moves rearwardly to sever the thread. This tightening of the thread also maintains tension on that part of the thread in the shed which might otherwise be lost 50 as a result of the cutting.

Downward motion of the placer 60 is of course attended by a corresponding forward motion of the hook 72, but since lever 20 will remain up during and for a short time subsequent to transfer, provision must be made for permitting forward motion of the hook. It is for this reason that I form the lever 75 of the parts shown in Fig. 6. When lever 75 moves to the dotted position shown in Fig. 1 it first moves the hook rearwardly 55 to raise the placer 60, after which the lever continues to turn until shoulder 85 lifts the hook out of holding engagement with the plate 82 before part 95 engages the thread placer. As the shuttle feeler lowers the wire 60 the rear end 60 of the hook will slide up along the surface 83 of plate 82. It is to be understood of course that the frictional device shown in Fig. 4 will hold the wire or placer 60 in raised position after shoulder 85 disengages the hook 72 from arm 75.

If, on the other hand, the shuttle is not properly placed it will interfere with rearward motion 70 of the shuttle feeler and the arm 30 will not be able to reach the dotted line position shown in Fig. 1. Under these conditions the two parts 75 24 and 25 of head 18 will separate to permit an

upward sliding of the stud 23 as lever 20 rises, as described in the aforesaid Patent No. 2,162,290. Since the shuttle feeler engages the thread placer during the latter part only of its motion toward shuttle detecting position, the lever 58 will not 5 be rocked and the placer 60 will remain elevated without moving the weft into the tube 50. On the next pick therefore the thread, not having been cut, will not be held by the wire 60 but will be drawn into the shed in the usual manner. On 10 a subsequent pick when the shuttle is properly placed the thread will be severed and the thread placer lowered as already described.

When the wire descends as in the position shown in Fig. 5 it will be held down by friction 15 and when sub-atmospheric pressures next exist in the accumulator 48, an inrushing column of air moving downwardly through the slot 52 will draw into the tube 50 that part of the thread extending from the cutter 46 to the slot 52. This 20 action ordinarily occurs when the shuttle is picked, thereby releasing the thread. When the thread is severed at the selvage on a subsequent beat of the lay, the remainder of the weft will be drawn into the tube 50. It will be noted that 25 the column of air moving into the tube 50 has a forward motion so that the thread will be drawn away from the bend 62 in the placer 60.

From the foregoing it will be seen that I have provided a thread remover for weft replenishing 30 looms comprising a pneumatic tube located under the path of the shuttle and having an inlet mouth or slot into which the thread is drawn. It will also be seen that the thread placer or wire 60 assists this removing operation by positively moving 35 a portion of the thread into the tube 50. Furthermore, the thread placer 60 is controlled by the shuttle feeler and does not descend if a misplaced shuttle revokes transfer by preventing a complete rearward motion of the shuttle feeler. 40 Another feature of my invention is the automatic disengagement between the lever 75 and the hook 72 after the hook has been moved rearwardly far enough to raise the wire 60 above the path of the shuttle. It is to be understood of course 45 that the placer 60 must be up before the shuttle arrives at the magazine end of the loom. Otherwise the descending wire 60 could not move the thread into the slot 52. Also, the space between the placer 60 and the bottom of tube 50, as suggested in Fig. 8, permits the thread to move forwardly from the parts 62 and 63 of the placer and thence through tube 41 to the accumulator. 50

Having thus described my invention it will be seen that changes and modifications may be made 55 therein by those skilled in the art without departing from the spirit and scope of the invention and I do not wish to be limited to the details herein disclosed, but what I claim is:

1. In a pneumatic thread removing mechanism 60 for a loom having a lay and a shuttle box thereon containing a shuttle from which a thread extends along the lay to the adjacent selvage, the loom having means to cut the thread between the shuttle eye and the selvage, that improvement 65 comprising a hollow member mounted on the lay under the path of the shuttle and having an intake mouth below the thread between the selvage and the means to cut the thread, means to push the thread downwardly through the intake mouth 70 into the hollow member, and means to induce a draft of air into the intake mouth to draw the thread into said hollow member.

2. In a pneumatic thread removing mechanism 75 for a loom having a lay and a shuttle box thereon

- containing a shuttle from which a thread extends along the lay to the adjacent selvage, the loom having means to cut the thread between the shuttle eye and the selvage, that improvement comprising a tube extending transversely of the lay under the path of the shuttle and having an elongated intake mouth extending transversely of the lay under the thread between the selvage and the means to cut the thread, a thread placer, means to move the thread placer downwardly on the thread and into the intake mouth to move a portion of the thread into the tube, and means to induce an inrush of air into the intake mouth to draw the remainder of the thread into the tube.
3. In a pneumatic thread removing mechanism for a loom having a lay and a shuttle box thereon containing a shuttle from which a thread extends along the lay to the adjacent selvage, the loom having means to cut the thread between the shuttle eye and the selvage, that improvement comprising a tube mounted on and moving with the lay and extending transversely of the latter under the path of the shuttle, said tube having an elongated intake mouth extending transversely of the lay under the thread between the selvage and the means to cut the thread, a thread placer above the thread, means to move the placer downwardly on to the thread and into the intake mouth to move a portion of the thread into the tube, and means to induce an inrush of air into the intake mouth to draw the remainder of the thread into the tube.
4. In a pneumatic thread removing mechanism for a loom having a lay and a shuttle box thereon containing a shuttle from which a thread extends along the lay to the adjacent selvage, the loom having means to cut the thread between the shuttle eye and the selvage, that improvement comprising a tube secured to and extending transversely of the lay under the path of the shuttle and having an intake mouth extending across the lay under the thread between the selvage and the means to cut the thread, a thread placer above the tube having a rear portion from the forward end of which an upwardly inclined part extends, means to move the placer downwardly on the thread and move said portion thereof into the tube to place part of the thread in said tube, and means to cause a column of air to move into the intake mouth and downwardly and forwardly with respect to the placer to draw the remainder of the thread into the tube and move the same forwardly away from the upwardly inclined part of the placer.
5. In a pneumatic thread removing mechanism for a loom having a lay and a shuttle box thereon containing a shuttle from which a thread extends along the lay to the adjacent selvage, the loom having means to cut the thread between the shuttle eye and the selvage, that improvement comprising a tube extending transversely of the lay under the path of the shuttle and having an elongated intake mouth extending transversely of the lay under the thread between the selvage and the means to cut the thread, a thread placer, means to move the thread placer downwardly on the thread and into the intake mouth to move a portion of the thread into the tube, and means to induce an inrush of air into the intake mouth to draw the remainder of the thread into the tube, the placer having a part at the rear end thereof behind the thread to prevent that portion of the placer in front of said part from engaging the bottom of the tube.
6. In a weft replenishing loom having a lay

and a shuttle box thereon containing a shuttle from which a thread extends along the lay to the adjacent selvage, the loom having a part to be moved preparatory to a replenishing operation and the loom also having provision for cutting the thread between the shuttle eye and said adjacent selvage, that improvement comprising a tube secured to the lay and extending transversely under the path of the shuttle, the tube having an elongated intake mouth extending transversely of and under the thread between the selvage and the means to cut the thread, a thread placer normally located in the tube under the thread, means operated by said part of the loom which moves preparatory to a replenishing operation to lift the thread placer to a position above the path of the shuttle prior to arrival of the shuttle in the shuttle box, means to move the thread placer downwardly on the thread after the shuttle has entered the shuttle box and move a portion of the thread into the intake mouth, and means to induce a draft of air into the intake mouth to draw the remainder of the thread into said tube.

7. In a weft replenishing loom having a lay and a shuttle box thereon containing a shuttle from which a thread extends along the lay to the adjacent selvage, the loom having provision for cutting the thread adjacent to the shuttle eye and having also a shuttle position detector movable across the path of the shuttle if the shuttle is properly boxed and prevented from moving across the path of the shuttle if the shuttle is improperly boxed on a replenishing beat of the loom, that improvement comprising a tube extending across the lay under the path of the shuttle and having an elongated intake mouth extending transversely of the lay under the thread between the selvage and the means to cut the thread, a thread placer above the thread, means operated by the shuttle positioning detector to move the placer down on the thread and into the intake mouth when the shuttle position detector moves across the shuttle path and thereby move a part of the thread into the tube, and means to induce an inrush of air into the intake mouth to draw the remainder of the thread into the tube.

8. In a weft replenishing loom having a lay provided with a shuttle box containing a shuttle from which a thread extends along the lay to the adjacent selvage, the loom having provision for cutting the thread adjacent the shuttle eye on weft replenishing beats thereof, and the loom having a part movable preparatory to a weft replenishing operation of the loom and having also a shuttle position detector to be moved across the path of the shuttle if the latter be properly boxed and be prevented from moving across said path if the shuttle be improperly boxed on a replenishing beat of the loom, that improvement comprising a hollow member mounted on the lay beneath the path of the shuttle, said hollow member having an intake mouth extending transversely of the lay under the thread between the selvage and the means to cut the thread, a thread placer normally located in the hollow member, means operated by said part of the weft replenishing loom to lift the placer through the intake mouth to a position above the path of the shuttle prior to movement of the shuttle over said intake mouth when moving toward the shuttle box, means operated by the shuttle position detector when the latter moves across the path of the shuttle due to proper boxing of the shuttle to move the thread placer downwardly on the

thread and into the intake mouth to draw a portion of the thread into the hollow member, and means to induce an inrush of air into the intake mouth to draw the remainder of the thread into said hollow member.

9. In a weft replenishing loom having a lay provided with a shuttle containing a shuttle from the eye of which a thread extends along the lay to the adjacent selvage, the loom having provision for cutting the thread adjacent the shuttle eye, that improvement comprising a hollow member secured to the lay below the shuttle path and having an intake mouth below the thread between the selvage and the means to cut the thread, a thread placer extending into the hollow member, means operative prior to passage of the shuttle over the hollow member on a weft replenishing beat of the loom to move the thread placer upwardly out of the intake mouth to a position above the shuttle path, friction means to hold the placer in raised position, means operative on a replenishing beat of the loom to move the placer downwardly on the thread and into the intake mouth to move a portion of the thread into the hollow member, and means to induce a draft of air into the intake mouth to draw the remainder of the thread into the hollow member.

10. In a weft replenishing loom having a lay provided with a shuttle box containing a shuttle from the eye of which a thread extends along the lay to the adjacent selvage, the loom having provision for cutting the thread adjacent the shuttle eye and having a part to be moved on a replenishing beat of the loom, that improvement comprising a hollow member secured to the lay under the shuttle path and having an intake mouth below the thread between the selvage and the means to cut the thread, a thread placer normally located within the hollow member, setting means

operated by said part and movable from one extreme position to another extreme position on a replenishing beat of the loom, an operating element connected to the thread placer to be moved by said setting means to lift the placer to a position above the shuttle path during the first part of the movement of said means from said one extreme position to said other extreme position, means to disconnect said element from the setting means before the latter reaches said other extreme position, means to lower the thread placer on to the thread and move a part thereof into the hollow member through the intake mouth while said means is at said other extreme of its motion, and means to induce a draft of air through the intake mouth to draw the remainder of the thread into the hollow member.

11. In a weft replenishing loom having a lay provided with a shuttle containing a shuttle from the eye of which a thread extends along the lay to the adjacent selvage, the loom having provision for cutting the thread adjacent the shuttle eye, that improvement comprising a hollow member secured to the lay below the shuttle path and having an intake mouth below the thread between the selvage and the means to cut the thread, a thread placer extending into the hollow member, means operative prior to passage of the shuttle over the hollow member on a weft replenishing beat of the loom to move the thread placer upwardly out of the intake mouth to a position above the shuttle path, means operative on a replenishing beat of the loom to move the placer downwardly on the thread and into the intake mouth to move a portion of the thread into the hollow member, and means to induce a draft of air into the intake mouth to draw the remainder of the thread into the hollow member.

ALBERT CEDERLUND. 40
